DISPENSING CONTAINER

Michael Janchick, Chicago, Ill.

Application May 23, 1940, Serial No. 336,860

3 Claims. (Cl. 221—79)

My invention relates to improvements in dispensing containers for paste compounds or the like.

Among the important objects of the invention are to provide a container of the non-collapsing type which embodies a minimum number of parts adapted for easy manipulation for expeditiously dispensing a selected amount of the contents thereof, will not get out of order, is adapted for prolonged use, is easy to refill, and comparatively inexpensive to manufacture.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in side elevation of a preferred embodiment of my invention,

Figure 2 is a view in vertical longitudinal section taken on the line 2—2 of Figure 1,

Figure 3 is a view in transverse section taken on the line 3—3 of Figure 2,

Figure 4 is a view in transverse section taken on the line 4—4 of Figure 2,

Figure 5 is a view in side elevation of the screw shaft,

Figure 6 is a view in perspective of the follower, and

Figure 7 is a view in bottom plan of the nozzle.

Referring to the drawings by numerals, in the illustrated embodiment thereof my improved container comprises a tubular, open-top body 1 of suitable rigid material, and preferably rectangular in cross section with beveled edges 2, an integral flat bottom 3, and an external shoulder 4 extending around said body adjacent the top

thereof, said body being provided with a pair of opposed internal guide ribs 5 extending along opposite sides of the same, respectively, centrally of said sides and preferably V-shaped transversely and formed integrally with the sides. A central, internal boss 6 is provided in the bottom 3, axially of the body, and having a conical bearing socket 7 therein. The purpose of the guide ribs 5 and socket 7 will presently appear.

Fitting over the top end of the body 1, against the shoulder 4 is a cap member 8 having an edge flange 9 which may be secured in any suitable manner to said body. The cap member 8 is provided with a central, circular discharge aperture 10 therein bridged by a diametrical bar 11 apertured to provide a bearing opening 12 there-

in, axially aligned with the bearing socket 7. The top of the cap member 8 is provided with an annular flat seat 13 countersunk in said top of said member to provide an annular guideway 14 therein concentric to the discharge aperture 10 and transversely square.

Surmounting the seat 13 for rotation thereon, is an upwardly tapering nozzle 15 terminating in a reduced externally threaded neck 16, said nozzle having a circular bottom edge 17 fitting flat on the seat 13 and in the guideways 14 and said nozzle being undercut, as at 18, to overlie the top of the cap member 8 around the outer sides of said guideways. As will be understood, the nozzle 15 covers the discharge aperture 10. A closure cap 19 is threaded onto the neck 16. The nozzle 15, and closure cap 19 may be fluted to facilitate gripping and turning the same.

An axial screw shaft 20 is provided in the body 1 with a lower pointed end 21 fitting in the socket 7 and its upper end having a working fit in the bearing opening 12 of bar 11 and extending for a short distance above said bar. A collar 22 suitably fixed on said shaft 20 and bearing against the under face of the bar 11 blocks endwise movement of said shaft 20 outwardly. A washer 23 is provided on the extended end of the shaft 20 to bear against the outer face of the bar 11 for a purpose presently seen. A pin 24 threaded into the nozzle 15 diametrically thereof and extended through an aperture 25 in the extended end of the shaft 20 keys the nozzle to the shaft and retains the bottom edge 17 of the nozzle against the seat 13 and in guideways 14, said pin also passing over the washer 23 to retain the same on the shaft 20 and against the bar 11 so as to seal the bearing opening 12 on the top side of said bar.

Within the body 1, is a substantially rectangular, plate-like follower 26 fitting therein with a slight clearance and provided with edge notches 27 by means of which it is slidably mounted on the guide ribs 5, said follower having a central boss 28 through which the shaft 20 is threaded so that rotation of the latter in opposite directions moves the follower outwardly and inwardly of the body 1.

As will now be seen, rotation of the nozzle 15 in the proper direction will impart rotation to the shaft 20 in a direction to cause the follower 26 to move outwardly of the body 1 and thereby force the contents of the body out of said nozzle 15 by way of discharge aperture 10.

To refill the body 1 it is merely necessary to remove the pin 24, whereupon the nozzle 15 may

be detached and the body 1 filled through the discharge aperture 10. As will be understood, prior to refilling, the nozzle 15 should be rotated in the proper direction to cause the screw shaft 20 to feed the follower inwardly of the body to the bottom 3 of the same.

The foregoing will, it is believed, suffice to impart a clear understanding of my invention without further explanation.

10 Manifestly the invention, as described, is susceptible of modification without departing from the inventive concept, and right is herein reserved to such modifications as fall within the scope of the subjoined claims.

15 What I claim is—

1. A dispensing container comprising a tubular body having an open upper end, a cap member fitting over said end of the body and having a central discharge aperture therein and a cross bar extending diametrically of said aperture, said member being provided in the outer face thereof with an annular guideway square in cross section, said guideway surrounding said aperture and concentric thereto, an outwardly tapering 25 nozzle member surmounting the cap member and having an inner edge fitted in said guideway for rotation therein, a central longitudinally extending screw shaft in said body having an end journalled in said bar, means detachably attaching 30 said nozzle member to said end of the shaft whereby said shaft is rotatable upon rotation of said nozzle member, and a follower in said body through which said shaft is threaded to be fed longitudinally of the body under rotation of said 35 shaft.

2. A dispensing container comprising a tubular body having an open upper end, a cap member fitting over said end of the body and having a central discharge aperture therein and a cross 40 bar extending diametrically of said aperture, said member being provided in the outer face thereof

with an annular guideway square in cross section, said guideway surrounding said aperture and concentric thereto, an outwardly tapering nozzle member surmounting the cap member and having an inner edge fitted in said guideway for rotation therein, a central longitudinally extending screw shaft in said body having an end journalled in said bar, means detachably attaching 5 said nozzle member to said end of the shaft whereby said shaft is rotatable upon rotation of 10 said nozzle member, and a follower in said body through which said shaft is threaded to be fed longitudinally of the body under rotation of said shaft, said means comprising a pin extended into said nozzle member transversely thereof and 15 passing diametrically through said end of the shaft.

3. A dispensing container comprising a tubular body having an open upper end, a cap member fitting over said end of the body and having a 20 central discharge aperture therein and a cross bar extending diametrically of said aperture, said member being provided in the outer face thereof with an annular guideway square in cross section, said guideway surrounding said aperture 25 and concentric thereto, an outwardly tapering nozzle member surmounting the cap member and having an inner edge fitted in said guideway for rotation therein, a central longitudinally extending screw shaft in said body having 30 an end journalled in said bar, means detachably attaching said nozzle member to said end of the shaft whereby said shaft is rotatable upon rotation of said nozzle member, and a follower in said body through which said shaft is threaded to be fed longitudinally of the body under rotation of 35 said shaft, said body having longitudinal internal guide ribs therein for said follower, and the follower having notches in edges thereof for straddling said ribs.

MICHAEL JANCHICK. 40
